TRASH CLEARING DEVICE FOR HARROW
TEETH AND THE LIKE

Leo Cieslak, Salem, Oreg.

Application November 12, 1946, Serial No. 709,233

6 Claims. (Cl. 97—194)

1

This invention relates to improvements in harrows and cultivators and is particularly adapted to be used in connection with spring tooth harrows.

The primary object of the invention is to provide an attachment for harrows and cultivators that will remove grass, weeds and the like from the teeth of the harrows without having to stop the harrow in its operation.

A further object of my invention is to provide a device of this nature that can be readily attached or detached from the implement.

My invention consists of providing endless hold down elements located between the teeth or shoe of the harrows or cultivators for holding the vegetation against the ground surface, thereby removing the same from the teeth of said implement. This hold down element consists of an endless chain, which will be more fully described and disclosed in the drawings and specification.

These and other incidental objects will be apparent in the drawings, specification and claims.

Referring to the drawings:

Figure 1 is a plan view of a single section of a conventional spring tooth harrow, having my new and improved tooth or shoe clearing elements mounted thereon.

Figure 2 is a side sectional view taken on line 2—2 of Figure 1.

Figure 3 is a fragmentary enlarged detail view illustrating a preferred method of mounting my new and improved tooth or shoe clearing device to a conventional spring tooth harrow.

Figure 4 is an enlarged fragmentary sectional side elevation illustrating the principle of operation of my new and improved tooth or shoe clearing device.

Figure 5 is a perspective view of the frame assembly.

In the drawings:

I have illustrated one section of a spring tooth harrow, which consists of the frame 1, having the cross frames 2 pivotally mounted therein at 3. The usual spring teeth 4 are secured to the cross frames 2. The position of these teeth and frames are controlled by the lever mechanism 5, including its control bars 6 and 7, said bars 7 being fixedly mounted to the cross frames 2 at 8. The above elements make up the usual spring tooth harrow assembly.

My invention consists in mounting endless chains 9, which I will term as hold down elements for holding down the vegetation being gathered by the teeth of the harrow against the ground surface, pulling the same away from these teeth

2

during the forward movement of the harrow, which will be more fully described in detail later on.

My new and improved tooth or shoe clearing device consists of frames 10 preferably a bar running longitudinal of the harrow assembly when mounted. Fixedly secured to one end of this bar is a forked bearing support 11 to which is journaled the sprocket 12. Formed on the opposite end of the bar 10 is a fork 13 which is adjustably mounted within the base 14 forming part of the bar 10.

A suitable adjusting screw 15 adjusts the position of the fork after which it is locked in this position by the clamp bolts 16. This provides for an adjustment of the chain 9, which must be maintained in a taut condition. This chain is trained about the sprocket 12 and the sprocket 17. Lugs 18 are provided on the chain for engaging the ground surface and holding the chain stationary relative to the ground during the forward movement of the implement.

The entire assembly of the frame 10, sprockets and chain, is mounted to the harrow in the following manner. Clamps 19 are secured to the cross frames 2 by the bolts 20. Forming part of the clamps 19 are brackets 21. Links 22 are pivotally mounted on their one end to the stub shafts 23 forming part of the forks 11 and 13, and are pivotally mounted to the brackets 21 at 24 at their opposite end. The clamps 19, brackets 21 and the links 22 securely mounts the hold down assembly to the implement. I have provided a resilient means for holding the hold down assembly down against the ground surface relative to the implement and this consists of pivotally mounting a rod 25 to the links 22 at 26 and slidably mounting its opposite end through the upturned portion 27 of the brackets 19.

40 A spring 28 is anchored to the rod 25 at 30 and bears against the upturned portion 27 of the bracket 19. This provides a downward force on the links 22 relative to the cross frames 2 of the implement regardless of the position given to the teeth 4 by the adjustment of the lever 5. An idler sprocket 31 is mounted midway the length of the frame 10 at 32 and bears down against the chain 6 adjacent the intermediate teeth 4 of the implement.

45 I will now describe the operation of my new and improved tooth or shoe clearing device. As the implement frame 1 and its associated teeth 4 are pulled over the ground surface the chain 6 of my clearing device contacts the ground surface, best illustrated in Figures 2 and 4. The

teeth 18 preventing the lower run of the chain from moving relative to the ground surface. This then holds down on the vegetation indicated at 33 which is being fouled around the tooth or shoe 4 at 34. The chain holds said vegetation down while the tooth moves forward relative to the ground surface and the chain. This is the primary object of my invention, the pulling of this vegetation away from the tooth or shoe as it tends to collect thereon.

I do not wish to be limited to the particular mechanical structure as shown and described as other mechanical equivalents may be substituted still coming within the scope of my claims.

I claim:

1. In a harrow including a tooth mounted on a frame, the combination with the improvements comprising a pair of idler wheels mounted on parallel axes in spaced relation transversely of said frame respectively in front of and behind said tooth, said wheels being in a plane laterally adjacent said tooth, and an endless member extending around said wheels for engagement by the bottom run thereof with the ground beside said tooth to hold down vegetable matter adjacent the path of said tooth as the harrow is moved over the ground.

2. In a harrow including a frame, a plurality of cross-bars in said frame and a plurality of spaced teeth mounted on each bar, the combination of the improvements comprising a plurality of pairs of idler wheels respectively mounted in the front and rear of said frame on parallel axes, each pair of wheels lying in a plane laterally adjacent one of said teeth on each of said cross-bars, and an endless member extending around each pair of wheels for engagement by the bottom run thereof with the ground beside the respective teeth to hold down vegetation adjacent the path of said teeth as the harrow is moved over the ground.

3. In a harrow having a plurality of teeth carried on a frame, a plurality of endless members mounted on the frame to extend in the direction of movement of the harrow with the bottom runs in contact with the ground in close proximity to the harrow teeth to hold down vegetation in the path of the teeth, pairs of rotatably mounted wheels respectively supporting said endless members and being longitudinally spaced by rigid members, and links pivotally connecting the mountings of said wheels with the frame to effect vertical movement of said wheels and endless members relative to said frame.

4. In a harrow having a plurality of teeth carried on a frame, a plurality of endless members mounted on the frame to extend in the direction

of movement of the harrow with the bottom runs in contact with the ground in close proximity to the harrow teeth to hold down vegetation in the path of the teeth, pairs of rotatably mounted wheels respectively supporting said endless members and being longitudinally spaced by rigid members, links pivotally connecting the mountings of said wheels with the frame to effect vertical movement of said wheels and endless members relative to said frame, and means resiliently biasing the wheels and endless members downwardly relative to said frame.

5. In a harrow having a plurality of teeth carried on a frame, a plurality of endless members mounted on the frame to extend in the direction of movement of the harrow with the bottom runs in contact with the ground in close proximity to the harrow teeth to hold down vegetation in the path of the teeth, pair of rotatably mounted wheels respectively supporting said endless members and being longitudinally spaced by rigid members, links pivotally connecting the mountings of said wheels with the frame to effect vertical movement of said wheels and endless members relative to said frame, a rod pivotally connected to each of said links and slidably supported by said frame, and a compression spring coiled about each of said rods between the link and frame to resiliently bias the wheels and endless members downwardly relative to said frame.

6. In a harrow having a plurality of teeth carried on a frame, a plurality of endless members mounted on the frame to extend in the direction of movement of the harrow with the bottom runs in contact with the ground in close proximity to the harrow teeth to hold down vegetation in the path of the teeth, pairs of wheels respectively supporting said endless members, shafts rotatable supporting said wheels, pairs of means supporting the shafts of said pairs of wheels and supported at the opposite ends of a rigid bar to space the wheels of each pair, one of said means of each pair being adjustable longitudinally of said bar, and links pivotally connecting said shafts with said frame to effect vertical movement of said wheels and endless members relative to said frame.
